UNITED STATES PATENT OFFICE

ERNEST YEOMAN ROBINSON, OF MANCHESTER, ENGLAND.

VACUUM ELECTRIC TUBE.

Application filed March 21, 1924. Serial No. 700,917.

To all whom it may concern:

Be it known that I, ERNEST YEOMAN ROBINSON, a subject of the King of Great Britain, and a resident of Withington, 5 Manchester, in the county of Lancaster, England, have invented a new and useful Improvement in or Relating to Vacuum Electric Tubes (for which I have filed an application in England, Feb. 14, 1923, Patent No. 217,273), of which the following is a specification.

In vacuum electric tubes such for example as those containing an electron emitting cathode and operating with a substantially 15 pure electron discharge in a high vacuum, it is usual during the process of evacuation to heat the anode by suitable means such as by a thermionic bombardment in order that the anode may be freed of occluded 20 gases and the like. When these vacuum tubes are built in large sizes it is desirable to circulate a cooling fluid round the anode or within the anode in order to cool the said anode. Furthermore, it is also sometimes 25 desirable that a portion of the containing envelope should be metallic, and it is sometimes arranged that when a portion of the envelope is metallic then this metallic portion serves as the anode and is arranged to 30 be fluid cooled.

As hereinbefore stated it is the practice to heat the anodes and other electrodes of vacuum devices to a high temperature during evacuation in order to get rid of the occluded gases; it is possible to do this because the electrodes are supported from the vitreous container by thin stems, which stems do not conduct heat readily to the vitreous container. Now when the anode is water 35 cooled, or when a portion of the containing envelope is metallic, it is impossible to heat such metallic members to a higher degree than the vitreous container, because the metallic members are in good heat contact 40 therewith. In consequence of this, evacuation of the device must be effected with the metallic electrodes or members at a low temperature. This results in the time of evacuation being greatly prolonged.

According to this invention means are provided whereby the electrodes or metallic members which may constitute part of the envelope of a vacuum electric tube may be cooled in the neighbourhood of the seal while 45 they are heated to a high temperature over

the remainder of their surface. During evacuation of the device, this cooling of the electrodes in the neighbourhood of the seal is preferably effected by arranging that a cool body is in heat contact with the electrodes or members in proximity to the seal. The cool body may preferably be itself water cooled. Moreover, it is preferably arranged that where the electrode is of a metal which oxidizes, such for example as copper or 60 nickel, the heating of the electrodes may be effected in a non-oxidising atmosphere. The electrode or member may be heated in a reducing atmosphere, such as hydrogen, or in a vacuum; that is to say a vacuum may 65 be produced on its exterior, the interior of the electrode or member being of course evacuated. The electrode or member may be heated by an electronic bombardment from the cathode or it may be heated by 70 heat radiation from the cathode or from a source external to the device or by a combination of these means.

In carrying out the invention as applied 75 to a tube having an envelope comprising a metallic anode and vitreous part sealed together, the metallic anode being constructed for example of spun copper, said anode is heated during the evacuation of the tube to a high temperature such as by radiation 80 or by thermionic bombardment from the cathode or by a heater placed external to the valve or by inducing high frequency currents in the anode itself and is cooled in the neighbourhood of the seal between the anode 85 and the vitreous part by means of a water cooled chamber which is in good thermal contact with the anode in proximity to the seal. Alternatively the cooling liquid may be in direct contact with the anode in the neighbourhood of the seal and if desired with the seal itself. Or a combination of 90 these methods may be employed. The anode may be enclosed in the chamber which may be water jacketed if desired and which is 95 preferably either filled with a reducing or inactive gas which may be at a low pressure and may be for example hydrogen or nitrogen, or the chamber may be evacuated. 100 When the chamber is evacuated a gas-tight seal is made between the anode and the chamber and this may be effected by means for example of a rubber gland, a mercury or other liquid seal or sealing wax or the 105 like at the cooled portion of the anode. The 110

chamber may consist of metal or it may consist of an insulating material when it is desired to heat the anode by inducing high frequency currents therein and it may be of 5 glass or quartz in order to permit the anode being observed during the heating.

The best results are obtained when the chamber is evacuated since in such a case the anode may be heated to a higher temperature than if gas at say atmospheric pressure were present as in the latter case the temperature to which the anode may be heated is limited by the fact that it collapses and in the former case the temperature is 10 only limited by the volatilization or melting of the anode.

When the anode is located within the container and is water cooled the invention may be applied in a similar manner and a cooling body may be inserted in the anode at the point where it is sealed to the vitreous container or within the inlet and outlet cooling pipes of the anode when these latter are the portions which are sealed to the container 20 in order to cool them in proximity to the seal; that is to say, the cooling body is in thermal contact with the anode or the cooling pipes thereof in proximity to the seal and at the surface exterior to the interior 25 of the valve.

To enable the invention to be clearly understood it will now be described with reference to the accompanying drawings which are sectional elevations illustrating four different arrangements of apparatus in accordance with the invention for use in the removal of gases and vapours from electrodes of vacuum electric tube device.

In these drawings:—

40 Figure 1 is a side elevation, partly in section, of one embodiment of an apparatus capable of carrying out the present invention, the same being shown applied to a vacuum electric tube.

45 Fig. 2 is a similar view showing another embodiment of the invention applied to a vacuum electric tube.

Fig. 3 represents in central vertical section another embodiment of the invention 50 applied to a vacuum electric tube.

Fig. 4 is a sectional view of another embodiment of the invention applied to a vacuum electric tube of the type in which the anode is located within the envelope of the 55 tube.

Referring to the drawings the envelope of the valve therein illustrated consists of the vitreous portion 1 and a metallic portion 2 for example of copper, which portions are 60 sealed together at 6. The metallic portion 2 constitutes the anode of the device and during the operation thereof is arranged to be water cooled. The anode 2 consisting as it does of a large mass of metal will contain 65 a large quantity of gas and it is essential

that this gas should be removed during evacuation of the device. If the means provided in this invention were not employed the anode could not be heated to a temperature much higher than that to which the seal 70 6 can safely be heated and thus the permissible temperature of the anode when the valve is being evacuated is low, consequently evacuation of the device is a long and expensive process. Now by this invention it is 75 arranged that the anode is heated to a high temperature for the removal of the absorbed gases and also it is cooled in the neighbourhood of the seal. Further, it may be arranged that the exterior of the anode is 80 placed in a vacuum. In consequence of this, the anode may be heated to a very high temperature during evacuation, the absorbed gases are quickly evolved and the time of evacuating the device is reduced. 85

In some cases, the anode 2 is for convenience provided with a conical portion 8 in the neighbourhood of the seal 6, for a purpose which will be explained.

Referring to Fig. 1, the anode is cooled in the neighbourhood of its seal by means of the water cooled member 7 which advantageously comprises a rubber chamber and fits on to the conical portion of the anode. This member is in air tight connection with 90 the metal chamber formed of the tube 3 and the flanged disc 4, an outlet tube 5 being provided. The chamber makes an air tight joint with the anode 2 by means of the member 7, and the compressing discs 10. During 100 evacuation of the envelope through the tube 21, the anode 2 is heated. In the example shown this is effected by supplying electrical energy to a winding 17 of nickel chrome 105 wire or the like which is wound on an insulating tube 14 of quartz or the like. Laggings 18 is provided between the heater and the casing 3. Electrical connection is made to the heater by means of lead-in wires 19 which pass through rubber glands 20. The 110 tube 14 is maintained in position at one end by means of the annular projection 15 on the water cooled member 7 and at the other end by the registering flanges 16 which are 115 welded or otherwise fixed to the disc 4. By reason of the conical portion 8 of the anode the chamber composed of the members 3 and 4 may be easily removed from the valve anode. The air-tight joint between the member 7 and the portion 8 of the anode is provided by the rubber ring 9 which is compressed by a steel ring 10 and tensioning devices such as those shown at 11 and 13, four of which may be provided. Alternatively, the air tight joint may be made by means 125 of wax or mercury or the like or in the case where the heating chamber is not evacuated such air tight joint may be omitted. It is preferred that the chamber formed by the members 3 and 4 is evacuated when the 130

anode is heated during its heat treatment and for this purpose the tube 5 may be connected to an evacuating pump. Holes or other suitable air passages should be provided in order to permit air which is contained in the packing 18 to pass to the pump.

Alternatively the anode may be heated by thermionic bombardment from the cathode or in those cases in which the gap between the anode and the cathode is short the anode 19 may be heated to a sufficiently high temperature by heat radiated from the cathode.

Referring to the arrangement shown in Fig. 2, the chamber 3 has a cool metal ring portion 7 one end of which is in thermal contact with the anode 2 of the valve. The chamber 3 is provided with an outlet tube 5 for evacuation and is also provided with a heater in the manner described with reference to Fig. 1. An air-tight joint between the anode 2 and the annular portion 7 is made by means of the rubber gland 22. The metal body 7 is cooled by means of liquid preferably water which fills the space 23 constituted by an upward extension of the tube 3. It will be seen that in this case the liquid also cools both the anode in the proximity of the seal and the seal itself. Further, the liquid acts as a sealing liquid 25 and to accentuate the sealing effect the bottom of the space 23 may be filled with mercury.

In the arrangement illustrated in Fig. 3 the chamber 24 is constructed of quartz or glass for example and is sealed or otherwise fixed to the water cooled member 7 which is in thermal contact with the anode in the proximity of the seal. The anode of the valve is heated by a thermionic bombardment or heat radiated from the cathode or alternatively it may be heated by inducing high frequency currents therein. For this purpose the annular member 7 may be split radially in order to prevent circulating currents being induced therein. A high frequency winding may be arranged outside the chamber 24. An air tight joint between the cooled member 7 and the chamber 24 and between the member 7 and the anode 2 may be made of wax or the like and the chamber exhausted or alternatively it may merely be covered with a loose packing for example of asbestos and the chamber 24 may be filled with a non-oxidizing gas for example of hydrogen or nitrogen. For this purpose inlet and outlet pipes 25 and 26 are provided.

Referring finally to Fig. 4 which illustrates a cooling arrangement in accordance with the invention applied to a valve in which the anode is located within the vitreous envelope 1 thereof, the latter is provided with two reentrant tubes 27 and 28. The copper anode 2 which comprises as shown a tube closed at one end is sealed to

the reentrant tube 27. The other electrode or electrodes of the device are omitted from the figure for the sake of clearness. They may be supported, for example, from the lower reentrant tube 28. The cathode in 70 one arrangement may comprise a helix of tungsten wire surrounding the anode 2.

During the heat treatment of the device the anode is heated by means of a thermionic bombardment, for example, and is 75 cooled at the portion 29 thereof which is adjacent the seal 6 by means of the cooled body 7 through which the cooling fluid is circulated. The cooled body 7 is of annular form and to permit it to be inserted within the anode 2 it comprises two segmental portions which are distinct from one another so that the member may be sprung outwards to press against the inner wall of the anode. The two segments of the cooling member 7 are provided respectively with intake and 80 outlet pipes 30 and 31 and are connected together by a looped tube 32. The tubes 30, 31 and 32 are of sufficient length and sufficiently thin to permit the two members 7 85 being sprung outwards as previously mentioned. The tubes 30 and 31 pass through perforations in the upper end of the chamber 3 and are preferably soldered thereto to provide a gas-tight connection therewith. 90 The upper end of the valve envelope 1 is covered by means of a chamber 3 provided with the outlet 5 so that it may be evacuated. An air-tight joint between the chamber 3 and the envelope 1 is obtained by means of 100 a rubber ring 33 which is adapted to be compressed between a clamping ring 10 and the lower end of the chamber 3 by means of the tensioning devices 11 and 13 which are similar to those described in connection 105 with Fig. 1.

The electrode in the neighbourhood of the seal may be cooled by the direct agency of cooling fluid, for example, it may be cooled directly by liquid or it may be cooled by 110 a current of gas which is preferably non-oxidizing, but it is generally preferable to cool it by conduction and convection by contact with a body which is maintained cool by a circulating cooling liquid or medium, 115 as hereinbefore described.

Various modifications may be made without departing from the scope of the invention.

Whilst the invention has been described in its application to vacuum electric devices in which the metallic member is sealed or fixed directly to the vitreous portion it will be understood that it is applicable to vacuum electric devices in which the metallic member is sealed to the vitreous portion in other ways. For example the metallic member in proximity to the seal may have welded thereto another metal portion, which metal portion may be fused to the vitreous 120 125 130

portion of the device and may be of a material more suitable for this purpose; for example it may consist of nickel steel having a coefficient of expansion approximately equal to that of the glass employed, and it may be coated with copper to facilitate the sealing process.

I claim as my invention—

1. The step in the method of removing 10 gases and vapors from the metallic portion of the envelope of a vacuum electric tube, which metallic envelope portion is welded to a vitreous envelope portion, which consists in heating said metallic portion to a 15 temperature higher than that which the weld can withstand to release the gases and vapors from said metallic portion while substantially conductively diverting the heat away from that part of the metallic 20 envelope portion in the neighborhood of the weld and then removing the heat thus diverted substantially by convection, thus maintaining the weld at a sufficiently low temperature to protect it.
2. The method of removing gases and 25 vapors from an electrode which is welded to a vitreous portion of the envelope of a vacuum electric tube, which comprises evacuating the envelope, and heating said electrode 30 to a temperature substantially higher than that which the weld can withstand to release the gases and vapors from said electrode while diverting heat from that part of said electrode in the neighborhood of the weld 35 substantially by conduction through a body in thermal contact therewith and then removing the diverted heat from said body, thereby maintaining the weld at a temperature sufficiently low to protect it.
3. The method of removing gases and 40 vapors from an electrode which comprises the metallic envelope and is sealed to a vitreous portion of the envelope of a vacuum electric tube of the metallic container type, which 45 consists in evacuating the interior of the envelope, maintaining the exterior surface of the electrode in an environment substantially free from oxygen, and heating said electrode to a temperature which would be 50 sufficiently high to cause rapid oxidation in air and is higher than that which the seal can withstand to release the gases and vapors therefrom, while maintaining that part 55 of the electrode which is in the neighborhood of the seal between the electrode and the vitreous portion of the envelope at a temperature sufficiently lower than that to which the remainder of the electrode is heated to protect the seal.
4. The method of removing gases and 60 vapors from an electrode which comprises the metallic envelope and is sealed to a vitreous portion of the envelope of a vacuum electric tube of the metal container type, which consists in evacuating the interior of 65

the envelope maintaining the exterior surface of the electrode in a vacuum, and heating said electrode to a temperature which would be sufficiently high to cause collapsing thereof if exposed to atmospheric pressure and is higher than that which the seal can withstand to rapidly release the gases and vapors therefrom, while maintaining that part of the electrode which is in the neighborhood of the seal between the electrode and the vitreous portion of the envelope at a temperature sufficiently lower than that to which the remainder of the electrode is heated to protect the seal.

5. Apparatus for use in the removal of 70 gases and vapors from an electrode which is sealed to a vitreous portion of the envelope of a vacuum electric tube, which comprises a fluid-cooled heat-conducting body having a wall to surround and make thermal contact with the part of the electrode in the neighborhood of the seal, said body being operative to remove heat from said part of the electrode substantially by conduction 75 through said wall of the body.

6. Apparatus for use in the removal, by 80 heat and evacuation, of gases and vapors from an electrode which is sealed to a vitreous portion of the envelope of a vacuum electric tube and forms part of the envelope thereof, comprising a chamber adapted to enclose the electrode which is to be freed from gases and vapors, and a fluid cooled member attached to said chamber and adapted to make thermal contact with said electrode in the region thereof adjacent to the seal whereby heat will be removed from said electrode by conduction through said member.

7. Apparatus for use in the removal, by 85 heat and evacuation, of gases and vapors from an electrode which is sealed to a vitreous portion of the envelope of a vacuum electric tube and forms part of the envelope thereof, comprising a chamber formed to enclose the electrode which is to be freed from gases and vapors, a fluid cooled member partly closing one end of said chamber and adapted to make gas-tight connection 90 in the region thereof adjacent to the seal to cool said seal, and means for controlling the atmosphere within said chamber.

8. Apparatus for use in the removal, by 95 heat and evacuation, of gases and vapors from an electrode which is sealed to a vitreous portion of the envelope of a vacuum electric tube and forms part of the envelope thereof, comprising a chamber formed to enclose the electrode which is to be freed from gases and vapors and to make gas-tight connection therewith, means within said chamber for heating the electrode, a fluid-cooled member partly closing one end of said chamber and adapted to make thermal contact 100

with the electrode adjacent to the seal thereof to cool said seal, and means for controlling the atmosphere within said chamber.

9. Apparatus for use in the removal, by heat and evacuation, of gases and vapors from an electrode which is sealed to a vitreous portion of the envelope of a vacuum electric tube and forms part of the envelope thereof, comprising a chamber formed to enclose the electrode which is to be freed from gases and vapors, an inductive winding within said chamber for heating the electrode by high frequency electric currents, a fluid-cooled member hermetically sealing said chamber and adapted to make thermal and hermetically sealing contact with said electrode adjacent the seal thereof to cool the seal, and means for controlling the atmosphere within said chamber.
10. Apparatus for use in the removal, by heat and evacuation, of gases and vapors from an electrode which is sealed to a vitreous portion of the envelope of a vacuum electric tube and forms part of the envelope thereof, comprising a chamber formed to enclose the exterior surface of the electrode, means for producing a removable gas-tight seal between said chamber and the envelope, a tubular body partly closing one end of said chamber and adapted to surround and make removable thermal contact with said electrode in the neighborhood of the seal to cool the seal by conduction, means for permitting the circulation of cooling fluid through said body, and means for controlling the atmosphere within said chamber. 35
11. Apparatus for use in the removal, by heat and evacuation, of gases and vapors from an electrode which is sealed to a vitreous portion of the envelope of a vacuum electric tube and forms part of the envelope thereof, comprising a chamber formed to enclose the exterior surface of the electrode, means for producing a removable gas-tight seal between said chamber and the envelope, 40 a tubular body partly closing one end of said chamber and adapted to surround and make removable thermal contact with said electrode in the neighborhood of the seal to cool the seal by conduction, means for permitting the circulation of cooling fluid through said body, means for controlling the atmosphere within said chamber, and means located within said chamber for electrically heating the electrode. 45
12. In testimony whereof I have hereunto subscribed my name this 10th day of March 1924. 50

ERNEST YEOMAN ROBINSON. 55
